Int. Cl. D17—03

U.S. Cl. D56—1

FIG. 3

FIG. 1 is a side elevational view of a bass viol for use with an electric amplifier, showing my new design, the opposite side being substantially a mirror image thereof,

FIG. 2 is a front elevational view; and
FIG. 3 is a rear elevational view thereof.

Portions of the drawing figures have been stippled to indicate contrast in appearance.

I claim:

The ornamental design for a bass viol for use with an electric amplifier, as shown and described.
